[57] CLAIM

The ornamental design for a protective pad for a seat belt, as shown and described.

DESCRIPTION

FIG. 1 is a front elevational view of a protective pad for a seat belt showing our new design, the broken lines shown are for illustrative purposes only and form no part of the claimed design;

FIG. 2 is an enlarged front perspective view thereof;

FIG. 3 is a front elevational view thereof;

FIG. 4 is a side elevational view thereof;

FIG. 5 is a rear elevational view thereof;

FIG. 6 is a top plan view thereof.
